C. MUEHLEISEN & C. A. ALBRECHT,
DISTRIBUTING MECHANISM OF TYPOGRAPHICAL COMPOSING MACHINES.
APPLICATION FILED NOV. 25, 1916.

1,222,019.

Patented Apr. 10, 1917.

UNITED STATES PATENT OFFICE.

CARL MUEHLEISEN AND CHRISTIAN AUGUSTUS ALBRECHT, OF BERLIN, GERMANY,
ASSIGNORS TO MERGENTHALER LINOTYPE COMPANY, A CORPORATION OF NEW
YORK.

DISTRIBUTING MECHANISM OF TYPOGRAPHICAL COMPOSING-MACHINES.

1,222,019.

Specification of Letters Patent. Patented Apr. 10, 1917.

Application filed November 25, 1916. Serial No. 133,449.

To all whom it may concern:

Be it known that we, CARL MUEHLEISEN and CHRISTIAN AUGUSTUS ALBRECHT, citizens of the United States of America, both 5 residing at Chausseestrasse 23, Berlin, N. 4, in the Empire of Germany, have invented new and useful Improvements in the Distributing Mechanism of Typographical Composing-Machines, of which the following 10 is a specification.

This invention relates to typographical composing machines such as those known commercially under the trade-mark "Linotype," and particularly to distributing 15 mechanism therefor adapted to distribute matrices or type-dies (which latter are to be regarded as included in the term "matrices" as hereinafter used) to a plurality of magazines. Such distribution necessarily 20 involves separation of the matrices according to font to insure their delivery to the proper magazines, and their separation according to character so that they may be returned to the respective channels of the 25 particular magazine appropriate to the respective font.

In distributing mechanism of the above-named kind it is already known to effect the separation of matrices according to font 30 by or through differences in the contour of the matrices of the different fonts involved, and for this purpose use has already been made of inclined surfaces on the feet of the matrices coöoperating with a tongue on to 35 which the said matrices are caused to fall vertically and which, according to the direction of the inclined surface will deflect them to one side or to the other and thereby permit of their reaching the respective magazine. In this arrangement however, the 40 matrices are unguided during their fall on to the deflecting tongue, and when the inclined surfaces become worn, the matrices fail to reach the tongue in the vertical position necessary to insure their proper deflection and therefore they frequently fall into 45 the wrong magazine. The present invention overcomes this difficulty by providing means whereby the descending matrices are positively guided until they reach the tongue, and by pivoting the latter so that it will be moved aside by said matrices out of the path to be pursued by them after leaving the tongue.

The invention will now be described by 55 reference to the accompanying drawings which, as an example, represent one constructional form of said invention; in these drawings:—

Figure 1 is a side elevation of the pertinent portion of a composing machine provided with six-superposed magazines, in which each two adjacent magazines have a common deflecting channel wherein the matrices are diverted into the respective magazines; 60

Fig. 2 is a rear elevation of a part of Fig. 1, drawn to a larger scale than is that figure;

Fig. 3 is a portion of Fig. 1 drawn to 70 the same larger scale, and

Figs. 4 and 5 illustrate matrices of respectively different fonts.

In Figs. 1 and 2, *a* represents part of the machine frame, *b*¹, *b*², *b*³, *b*⁴, *b*⁵, *b*⁶ the six 75 superposed magazines of the usual form, each being flat and formed with longitudinal channels to receive and guide the matrices on their edges, and *c* is distributor which is pivotally attached to the frame *a*, 80 and, by a rotating cam *d* is oscillated so as to allow the matrices to fall into three juxtaposed deflecting channels *e*¹, *e*², *e*³. This arrangement of oscillating distributor forms no part of the present invention, but 85 is included in an application for separate Letters Patent. Each of the deflecting channels *e*¹, *e*², *e*³ is common to two magazines, *b*¹ and *b*², or *b*³ and *b*⁴, or *b*⁵ and *b*⁶ respectively. The matrices received in the channel *e*¹ and appertaining to the magazines *b*¹, *b*², differ from each other in respect of the special distinguishing contours of their feet, for example, the two matrices *f*¹ represented in Fig. 4 are those which appertain to 90 the magazine *b*¹, while the two matrices *f*² represented in Fig. 5 are those which appertain to the magazine *b*²; in other words the matrices *f*¹ are provided with cams *f*³ inclining say from left to right, and the matrices *f*² are provided with cams *f*⁴ inclining 95 upwardly say from right to left.

A tongue *g* movable to and fro on a stationary pivot *g*¹, is located above each pair *b*¹, *b*², or *b*³, *b*⁴, or *b*⁵, *b*⁶ of the magazines 100 and will operate in the manner best shown in Fig. 3. A tension spring *h* normally maintains the tongue in the position in

which it is shown in Fig. 3, and returns it to that position after deflection therefrom. At the lower end of each of the deflecting channels e^1 , e^2 , e^3 , are located a pair of continuously driven bands i^1 , i^2 which, as shown in Fig. 3, engage the front and rear edges of the matrices and positively move the said matrices downward; rotary motion is imparted to the bands through a pulley i , Fig. 2, which is itself rotated by any convenient means. When a matrix f^1 is thus engaged between the bands i^1 , i^2 , its inclined foot is pressed on to a roller k pivotally mounted upon a side arm projecting up from and rigid with the tongue g so that the said roller and tongue will, by the inclined cam f^3 , be pushed toward the right by the inclined surface at the foot of the matrix f^1 as shown in Fig. 1, and the matrix, on leaving the bands i^1 , i^2 , will consequently be directed into the magazine b^1 . When a matrix f^2 is engaged between the bands i^1 , i^2 , the tongue g will be moved leftward and that matrix, as it should do, will fall into the magazine b^2 .

The rollers k are preferably made of a yielding material such as leather, hard india rubber, wood, or the like, in order to prevent damage to the edges of the matrices which come into contact therewith, and it is also preferred to form the said rollers with grooved peripheries, as shown in Fig. 2, so as to constitute guides for the matrices.

Having described our invention, we declare that what we claim and desire to secure by Letters Patent is:—

1. In a typographical machine, the combination with a flat longitudinally channeled matrix magazine, a distributor, and a series of intermediate channels, one for each of those of the magazine, for guiding the distributed matrices endwise into the magazine, of means located in the intermediate channels for positively propelling the matrices therethrough.

2. In a typographical machine, the combination with a flat longitudinally channeled matrix magazine, a distributor, and a series of intermediate channels leading from the distributor to the corresponding channels of the magazine, and through which the matrices pass endwise by gravity from one to the other, of propelling means located in the channels and adapted to engage the matrices as they pass therethrough.

3. In a typographical machine, the combination of a magazine, a matrix distributor, a conductor for guiding the matrices on their edges in an endwise direction from the distributor to the magazine, and two continuously rotating bands arranged at opposite sides of the conductor to engage the matrices on their opposite edges as they pass to the magazine.

4. In a typographical composing machine,

the combination with a plurality of matrix magazines and a corresponding plurality of different fonts of matrices, the matrices of different fonts having their feet of respectively different contour, of a matrix distributor, a series of channels or conductors to receive the distributed matrices and leading to the entrances of adjacent magazines, a movable tongue between the entrances of said adjacent magazines, capable of deflection in opposite directions to guide the distributed matrices into one or other of said magazines, and means on the tongue co-operating with the feet of the matrices to so deflect the tongue.

5. In a typographical composing machine, the combination with a plurality of matrix magazines and a corresponding plurality of different fonts of matrices, the matrices of different fonts having their feet of respectively different contour, of a movable tongue between the entrances of adjacent magazines, capable of deflection in opposite directions to guide the matrices into one or other of said magazines, means on the tongue co-operating with the feet of the matrices to so deflect the tongue, a channel conducting matrices to the entrances of adjacent magazines, and means in the channel adapted to positively propel the matrices therethrough.

6. In a typographical composing machine, the combination with a plurality of matrix magazines and a corresponding plurality of different fonts of matrices, the matrices of different fonts having their feet of respectively different contour, of a movable tongue between the entrances of adjacent magazines, capable of deflection in opposite directions to guide the matrices into one or other of said magazines, a roller on the tongue co-operating with the feet of the matrices to so deflect them, a channel conducting matrices to the entrances of adjacent magazines, and means in the channel adapted to positively propel the matrices during their co-operation with the roller.

7. In a typographical composing machine, the combination with a plurality of matrix magazines and a corresponding plurality of different fonts of matrices, the matrices of different fonts having their feet of respectively different contour, of a movable tongue between the entrances of adjacent magazines, capable of deflection in opposite directions to guide the matrices into one or other of said magazines, means on the tongue co-operating with the feet of the matrices to so deflect the tongue, and a spring operatively connected to the tongue, adapted to return it to normal position.

8. In a typographical composing machine, the combination with a plurality of matrix magazines and a different font of matrices for each magazine, the matrices of different fonts having oppositely inclined cams on

- their feet, of a channel conducting matrices to the entrances of adjacent magazines, continuously rotating bands adapted to engage the matrices between them to positively 5 propel the matrices through said channel and into the magazine entrances, a movable tongue between the entrances of adjacent magazines, capable of deflection in opposite directions to guide the matrices into one or 10 other of said magazines, and a roller on the tongue coöperating with the cams of the matrices while the latter are engaged by the bands, to deflect the tongue in accordance with the direction of inclination of the 15 said cams.
9. In a typographical machine, the combination of a matrix distributer, a conductor to receive the distributed matrices and guide them on their edges in an endwise direction, 20 and means located in said conductor for positively propelling the matrices therethrough.
10. In a typographical machine, the combination of a matrix distributer, a conductor 25 through which the distributed matrices pass endwise, means for positively propelling matrices through said conductor, and movable means operated by the matrices while under the action of their propelling means 30 for deflecting them in different directions according to form.
11. In a typographical machine, the combination of a matrix distributer, a conductor through which the distributed matrices pass 35 endwise, means for positively propelling the matrices through said conductor, and a movable switch arranged in the path of the propelled matrices and adapted to be moved thereby to different deflecting positions according to the form of the matrices.
12. In a typographical machine comprising 40 matrices of different forms, the combination of a matrix distributer, a conductor through which the distributed matrices pass in an endwise direction, and movable means 45 adapted to be operated by the matrices while under guiding control of the conductor for deflecting them in different directions according to form.
13. In a typographical machine comprising 50 matrices of different form, the combination of a matrix distributer, a conductor through which the distributed matrices pass in an endwise direction, a movable switch 55 adapted to receive the matrices from the conductor and to deflect them in different directions according to form, and means operated by the matrices during their passage through the conductor for setting the switch in its proper position.
14. In a typographical machine comprising 60 matrices of different form, the combination of a matrix distributer, a conductor through which the distributed matrices pass in an endwise direction, a movable switch 65 adapted to receive the matrices from the conductor and to deflect them in different directions according to form, and means operated by the matrices during their passage through the conductor for setting the 70 switch in its proper position, said means comprising an arm rising from the switch and provided with a roller normally located in the path of travel of the matrices.
15. In a typographical machine comprising 75 two sets of matrices provided with oppositely inclined cam surfaces on their bottom edges, the combination of a distributing conductor through which the matrices travel in an endwise direction, a movable switch 80 adapted to receive the matrices from the conductor and to deflect them in different directions according to form, and means operated by the matrices during their travel through the conductor for setting the switch in its 85 proper position, said means comprising an arm rising from the switch and provided with a roller adapted to be engaged by the inclined surfaces of the matrices.

In witness whereof we have hereunto set 90 our hands in the presence of two witnesses.

CARL MUEHLEISEN.
CHRISTIAN AUGUSTUS ALBRECHT.
